TOP FOR REFRIGERANT CYLINDERS

Arthur Frederick Barker, Newark, Del., assignor to E. I.
du Pont de Nemours and Company, Wilmington, Del.,
a corporation of Delaware

Filed June 9, 1965, Ser. No. 85,642

Term of patent 14 years

(Cl. D58—3)

FIG. 2

FIG. 1

FIGURE 1 is a side elevational view of the top for a refrigerant cylinder showing the new design.

FIGURE 2 is a plan view of the top for the refrigerant cylinder.

The dominant features of this design reside in the portions shown in full lines.

I claim:

The ornamental design for a top for refrigerant cylinders, substantially as shown.
